NECKTIE AND LINING THEREFOR

Max Kleinmann, New York, N. Y., assignor, by
mesne assignments, to Dimple Tie Corporation,
New York, N. Y., a corporation of New York

Application April 15, 1940, Serial No. 329,619

4 Claims. (Cl. 2—146)

This invention relates generally to combined neckties with linings, and to linings for neckties, and more particularly to such linings which when embodied in a necktie cause the necktie to crease or to drape in a predetermined manner when the same is worn.

The present application includes certain improvements over my Patent No. 2,123,900 granted July 19, 1938; and over my copending applications Ser. No. 196,439 filed March 17, 1938; Ser. No. 222,530 filed August 1, 1938; and Ser. No. 270,753, filed April 29, 1939.

Among the objects of the present invention is the provision of a combined lining and tie or a necktie lining which, when incorporated in a four-in-hand or other type of necktie which is knotted or otherwise constricted when worn, causes the tie to form a drape, "dimple," or become longitudinally corrugated in a predetermined position with relation to the longitudinal side edges of the necktie.

Another object herein is the provision of a combined lining and tie or a necktie lining having a self draping feature whose structure will drape with equal facility whenever the lining is longitudinally stressed at any point along a predetermined area thereof, the drape being retained by a restriction about the tie, caused for example, by a knot therein.

Another object of the present invention is the provision of a self draping combined lining and tie or a necktie lining which is of very simple construction and adapted for quantity production at low cost.

The present invention discloses the construction of a self draping combined necktie and lining or a lining which has no parts which will be deleteriously affected by laundering, dry cleaning, pressing or wear.

An advantage of the present structure lies in the fact that no skill need be acquired and no new dressing or tying method need be learned or used by the wearer because the ordinary tying operation automatically forms the desired shape to the tie lining and necktie. The draped appearance of the knotted tie which results from the normal tying operation does not have an artificial stiff, or preformed appearance but appears to have a natural drape such as results when a cravat is skillfully and carefully tied. After the tie is untied and removed, the lining and tie resume their normal relatively flat appearance thereby making pressing, shipping or storage a simple matter.

A still further object of the present invention

lies in the quantity high speed production of necktie linings having the above described draping qualities, manufactured without the necessity of any folding operation; and the quantity high speed production of combined linings and ties requiring only a single folding of the necktie casing and a turning (rightside out) operation.

These objects and further features and advantages will more fully appear in the progress of this disclosure and be pointed out in the appended claims.

In the drawings, forming a material part of this disclosure, and in which similar reference characters designate corresponding parts throughout the several views of each embodiment:

Figure 1 is a view in perspective showing a necktie as worn and including the present invention. In this view the lining is within the necktie in its "normal" position, that is, with the lining arranged to form a centrally disposed depression bordered on either side by a corresponding elevation or bulge.

Figure 2 is a view taken similarly to Figure 1, but in this view the tie lining is reversed from its "normal" position so that the lining forms a centrally disposed bulge or elevation bordered on either side by a corresponding depression or groove.

Figure 3 is a fragmentary elevational view of a necktie lining illustrating a first embodiment of the invention. In this view, the lining is in the "normal" position thereof corresponding to Figure 1 and is unstressed.

Figure 4 is a fragmentary rear elevational view of the embodiment illustrated in Figure 3.

Figure 5 is a fragmentary schematic front elevational view greatly enlarged showing in detail the arrangement of the various threads forming the draping means. In this figure the textile material forming the foundation upon which the threads are formed into stitches is removed for purposes of clarity.

Figure 6 is a fragmentary elevational view of the embodiment illustrated in Figure 3 but shows the lining in a stressed condition.

Figure 7 is a fragmentary rear elevational view of Figure 6.

Figure 8 is a fragmentary side elevational view as seen from the left side of Figure 6 or the right side of Figure 7.

Figure 9 is an enlarged sectional view as taken from the plane 9—9 on Figure 3.

Figure 9A is an enlarged transverse sectional

view taken similarly to Figure 9 showing however the necktie lining as corrugated or creased when the lining is longitudinally stretched.

Figure 10 is an enlarged transverse sectional view taken similarly to Figure 9A but showing the tie body in addition and also the altered position of the parts when the tie body or casing is introduced.

Figure 11 is an enlarged transverse sectional view as seen from the plane 11—11 on Figure 1 showing only the front portion or larger wing of the tie body and the enclosed lining.

Figure 12 is an enlarged fragmentary front elevational view taken similarly to Figure 3 and showing in detail the arrangement of the various threads forming the draping means. In this view the lining is in the "normal" position thereof and is unstretched.

Figure 13 is a fragmentary front elevational view corresponding to Figure 12 but showing the parts in a stressed condition.

Figure 14 is a fragmentary view of a second embodiment of the present invention in one stage of the manufacture thereof. In this figure the necktie casing is inside out and the rear surface of the lining is seen.

Figure 15 is a transverse sectional view of a necktie made in accordance with the second embodiment of the invention. This view shows the stage in the manufacture of the necktie following the stage illustrated in Figure 14.

Turning to Figures 1, and 3 to 13 inclusive, a necktie generally indicated by numeral 20 includes a front portion 21, a draping portion 22, and a knot 23. A lining blank 24 is preferably of such width as to conform to the shape of the necktie casing 25 in which it is enclosed in the completed necktie. The blank 24 tapers outwardly at its longitudinal side edges 27 and 28 toward its lower wider end portion 29.

The lining blank 24 is composed of any suitably resilient material, preferably however, of woolen cloth cut on the bias (indicated at 30) as is well known in the art to which the present invention pertains.

The draping means generally indicated by numeral 26 comprises a plurality of thread elements 31, 41, and 51, preferably composed of relatively inelastic cord or thread.

The thread 31 is brought downwardly and forwardly through the blank 24 at a point 33 which is located on a first portion of the lining blank or a first imaginary longitudinal axis or line along which it is desired that the lining (and hence the tie casing 25) will form a fold or edge of a drape. Thread 31 is then bent or turned upon itself to form the bight A and passed rearwardly through the blank 24 at the point 33. In passing to the rear of the blank the thread 31 thus may contact itself. Thread 31 is continued downwardly along said first axis or line at the rear surface of the lining a suitable distance forming a thread portion 34 and is then brought forwardly through the blank 24 at a point 35. Next a bight B is formed similarly to the bight A. The thread 31 is again passed rearwardly through the blank 24 at the point 35 and continues downwardly along the rear surface of the blank 24 forming a thread portion 36. At point 37 the bight C is formed and in a similar manner this procedure is repeated forming a series of bights like the bights A, B, and C interconnected by the thread portions similar to the thread portions 34, 36 and 38.

The thread 41 is brought downwardly and for-

wardly through the blank 24 at a point 43 which is located on a second portion of the lining blank or a second imaginary longitudinal axis or line along which it is desired that the lining (and hence the tie) will form a fold or edge of a drape. The thread 41 is then bent or turned upon itself to form the loop R and passed rearwardly through the blank 24 at the point 43. In passing to the rear of the blank the thread 41 thus may contact itself. Thread 41 is continued downwardly along said second axis or line at the rear surface of the lining a suitable distance forming a thread portion 44 and is then brought forwardly through the blank 24 at a point 45. Next a loop S is formed similarly to the loop R. The thread 41 is again passed rearwardly through the blank 24 at the point 45 and continues downwardly along the rear surface of the blank forming a thread portion 46. At point 47 a loop T is formed and in a similar manner this procedure is repeated forming a series of loops like the loops R, S, and T interconnected by the thread portions 44, 46, and 48.

The thread 51 is disposed on the front surface of the lining blank 24. Since the interlacing of the threads 31, 41, and 51 occurs as a continuing series, a description of two cycles of movement of the thread 51 will suffice. As seen best in Figures 5 and 12 of the accompanying drawings the thread 51 is passed downwardly and forwardly through the bight A forming portion 52, then through the loop R. The thread 51 is then bent upon itself to form a loop H which encircles the loop S and then continues upwardly forming thread portion 53. The thread portion 53 goes through the loop R and changes its direction to form the thread portion 54 which travels downwardly and encircles the bight B. Leaving bight B thread 51 travels upwardly forming thread portion 55 which passes through the bight A. Leaving bight A, thread 51 travels downwardly forming thread portion 56 and thence downwardly through the bight B passing over the thread portion 54, and forming portion 62 (Fig. 12), then through the loop S. The thread 52 is next bent upon itself to form a loop I which encircles the loop T and then continues upwardly forming thread portion 63. The thread portion 63 goes through the loop S and changes its direction to form the thread portion 64 which travels downwardly and encircles the bight C. Leaving the bight C thread 51 travels upwardly forming the thread portion 65 which passes through the bight B. Leaving bight B thread 51 travels downwardly forming thread portion 66 and thence downwardly through the bight C passing over the thread portion 64, and forming portion 72.

From point 37 the stitching as described is repeated, resulting in the formation of a plurality of stitch portions corresponding to the stitch portions 52—56, and 62—66, both inclusive and in the formation of a plurality of loops corresponding to the loops G, H, and I.

The thread elements 31, 41, and 51 are each relatively inelastic, and are preferably strong, light in weight, and smooth on the outer surface thereof so that they may readily slip through the portions of the lining blank through which they pass and through the bights and loops also.

Each of the above described thread elements 31, 41, and 51, includes a plurality of thread portions. By reason of the positioning or arrangement of the thread elements these thread portions are disposed in different directions with relation to the longitudinal axis of the lining blank 24.

Each of the thread elements has certain portions thereof arranged longitudinally of the lining blank and certain other portions arranged at an angle to the longitudinal axis of the lining blank. The angularly disposed portions will contain both longitudinal components or units and transverse components or units. The thread portions arranged parallel to the longitudinal axis of the lining blank will contain only longitudinal components or units; while thread portions arranged at right angles to the longitudinal axis of the lining blank will contain only transverse components or units.

When the blank 24 is longitudinally stretched, in order to extend themselves with the lining blank, the threads 31, 44, and 54 must take a more nearly rectilinear course. This results in the lengthening of the thread portions containing only longitudinal components or units, or a preponderance of longitudinal components or units. This lengthening requires more thread which is taken up from the thread portions containing transverse components or units, and these last mentioned portions contract.

Specifically, when the thread portions 34, 36 and 38 and other portions corresponding thereto are lengthened by the longitudinal stretching of the lining, the bights A, B, and C and the other bights corresponding thereto are contracted. Similarly the lengthening of the thread portions 44, 46, and 48 and other thread portions corresponding thereto causes the loops R, S, and T, and other loops corresponding thereto to contract. Lengthening of the thread portions 55, 56 and 65, 66 and other thread portions corresponding thereto causes the loops G, H, and I and other loops corresponding thereto to contract.

The contracting thread portions and loops in so contracting must move the points 33, 35, and 37 and the other points corresponding thereto; and the points 43, 45, and 47 and the other points corresponding thereto, toward each other, causing the portions 39 of the blank which lie transversely between said points to pucker or gather. The thread portions containing transverse components or units prevent the lining blank portions 39 from moving forwardly (as viewed in Fig. 3) so that the portions 39 gather or pucker rearwardly of the blank 24 and thereby form a centrally longitudinally disposed groove, corrugation or furrow 40 for substantially the entire distance which the draping means 26 occupies.

The edges 21 and 28 when uninhibited will rise to take a position indicated in Figure 9A. When the lining is enclosed within the casing 25, however, the casing will cause the lining to take the shape indicated in Figure 10. Because of the flattened tubular shape of the casing, the front portion 21 and the drape portion 22 will follow the contour of the lining to form a corresponding drape 61. The draping effect of the casing 25 is more readily obtained when said casing is fabricated from woven material and cut on the bias as is well known in the art.

It may be noted at this point that the drape 61 and the furrow 40 are formed only when the lining blank 24 is under stress, but this drape effect is retained in the draping portion 22 by the constriction of the parts caused by the knot 23. When the necktie is knotted it will of course be understood that the lining blank 24 and the casing 25 are both longitudinally stressed or stretched as the knot 23 is made tight. When the blank 24 forms a groove 40 at the knot 23, the knot 23 also

forces the casing 25 to fall into groove or furrow 40 forming the drape 61.

While the illustrated relative spacing of the points 33, 35, and 37 from each other; and the points 43, 45, and 47 from each other; and the spacing of the row of points 33, 35, 37 from the row of points 43, 45, 47; have all been found satisfactory in use (Figures 3 and 4 showing actual size spacing of said points in one commercially successful form) said spacings may be varied without departing from the scope of the appended claims. Among the variations which may be produced are the following: If the spacing is increased between the row of points 33, 35, 37 and the row 43, 45, 47, without increasing the spacing between points 33, 35, and 37, and without increasing the spacing between points 43, 45, and 47, a greater longitudinal extension of the lining blank will be required to get a sufficient draping effect. Reducing the distance between the points 33, 35 and 37; and also between the points 43, 45, and 47, but not between the vertical rows of points will result in the formation of more thread portions containing transverse components and a relative reduction in the ratio of thread portions containing a predominance of longitudinal components, and a limit will be approached when insufficient groove formation will occur upon longitudinal stress. Increasing the spacing between the vertical rows of points and also the spacing between the points in each vertical row will increase the depth of the furrow 40 but when this is too deep, the casing is unable to follow said furrow because the thread portions 35 containing transverse components or units prevent the casing from falling into the furrow. Reducing the spacing between the row of points 33, 35, 37; and the row of points 43, 45, 47, will cause contraction to take place nearer the apex 108 of the angle formed by the sides of the furrow, and because of the leverage effect, the draping or grooving action will be amplified and yet the stitches are located so deeply in the furrow that they do not interfere with the falling of the casing into the furrow. A limit will be approached however, when the vertical rows of points are so close together that the grooving effect is lost since the thread portions will have practically no transverse components.

50 In the operation of the invention it is to be noted that when the lining blank is under longitudinal stress, by reason of the fact that it is composed of elastic material, there will be a lateral contraction thereof. In other words, the row of points 33, 35, 37, and the row of points 43, 45, 47 will move toward each other even when the draping means 26 is not installed in the lining. In order to form a groove or furrow it is necessary that these vertical rows of points approach each other to a greater degree or at a greater rate than would normally occur by reason of the lateral or transverse contraction of the lining blank. This additional contraction is performed by the thread portions containing the transverse components 65 which are in turn actuated by the thread portions containing the longitudinal components.

The distance between the points 32 and 32' (when the lining blank is unstressed) is determined by the probable area on the tie which may be knotted throughout the life of the cravat; or if desired the row of stitches (draping means 26) may be extended to include the entire length of the lining—that is, the larger wing, the neck band portion and the smaller wing.

A feature of the present invention lies in the fact that the draping effect is not limited to any one portion of the necktie, but may be so arranged that any area usually likely to be disposed in or adjacent to the knot may be caused to drape and remain so draped until the knot is opened and the portion released, and this is also true regardless of the number of times that the tie may be coiled about itself in the formation of a knot.

In Fig. 2 the position of the lining blank 24 is reversed front to back. In this position the furrow 40 projects forwardly of the tie casing 44 and a drape or pucker occurs on either side thereof which is followed by the casing to form a double draped effect including the drapes 82 and 83.

Governed solely by the ultimate dimensions of the finished necktie it is of course possible, when desired, to run a plurality of threads 31, 41 and 51 in spaced relation to each other and longitudinally disposed. This will result in an increased number of furrows 49 in the lining blank 24 and corresponding grooves or drapes 61.

The completed lining blank 24 with the draping means 26 installed therein may be incorporated into the necktie 20 in any suitable manner as by means of a single row of ordinary slip stitching as is well known in the art.

In accordance with the second embodiment of the invention the slip stitching is not required and the draping means 26' serves also to attach the casing 25' to the lining blank 24' (see Figs. 14 and 15), with no loss in the resiliency of the finished necktie over the known slip stitch construction.

The casing 25' of the necktie 20' in its developed or blank form may be the usual blank as presently employed in the art. The method of making the second embodiment is substantially as follows. The necktie casing 25' is folded along its central longitudinal axis 50' with the "wrong" or "back" side outermost. When the necktie casing 25' is thus folded the longitudinal free edges 74' and 75' are preferably aligned so as to be coterminous, and the folded casing is placed on a flat surface. If desired, the central longitudinal axis of the lining blank may be visually indicated by any suitable mark or device. The lining blank is next placed on the uppermost surface of the folded casing with the longitudinal axis of the lining adjacent the said edges 74 and 75, the positioning of the lining blank being such that the draping means 26' will have the stitches thereof corresponding to the stitches 31 and 41 penetrating both layers of the casing and the lining blank.

Next a row of stitching or draping means 26' is installed, the thread element 51' being on the then upper surface of the lining, as is seen in Figure 14. Since the stitching in the draping means 26' is identical with that of the draping means 26 a detailed description thereof is not considered necessary. It will be noted however, that the thread portions corresponding to the thread portions 34, 36, 38, and 44, 46, and 48 are disposed on what will be rear portions of the casing 25' adjacent the edge 74', and these thread portions will be concealed in the finished tie, as seen in Figure 15.

The stitching having now been completed it is only necessary to turn the entire tie casing 25' and lining 24' inside or "right" side out. The

necktie 20' will then appear as in Figures 1 and 15, and the edges or folds 76' and 77' may be pressed as is well known in the art.

The stitching shown in the draping means 26 and 26' may be performed by sewing machine using a three thread, two needle machine with looper. In accordance with the second embodiment, the draping means 26' may run the whole length of the tie, taking the place of the usual slip stitching, or it may be used for only a part, and the remainder of the necktie may be constructed with any other desired type of stitching.

The foregoing description has been made rather detailed for clearness of understanding only and no unnecessary limitations should be understood therefrom but the appended claims should be construed as broadly as permissible in view of the prior art.

I claim:

1. In a necktie of the four-in-hand type having a lining wherein stitching is provided in the knot forming area thereof, the said stitching being so arranged that a dimple or drape will automatically form when the necktie is made up into a knot, that improvement in said stitching arrangement which comprises providing at least three thread sections, the first thread section passing through the lining of said necktie at spaced points along the length thereof in such manner as to form free loops of said thread at such points, the second thread section passing through the lining of said necktie at spaced points along the length thereof in such manner as to form free loops of thread at such points, the said free loops of said first and second thread sections being spaced from each other across the width of said lining and the third thread section passing freely through the said loops of said first and second sections to interconnect the same.

2. A necktie according to claim 1 in which the said third thread section is disposed entirely on one side of said lining.

3. A necktie according to claim 1 in which the said loops of said first and second thread sections as well as the third thread section are disposed on one side of the lining.

4. In a necktie of the four-in-hand type having a lining wherein stitching is provided in the knot forming area thereof, the said stitching being so arranged that a dimple or drape will automatically form when the necktie is made up into a knot, that improvement in said stitching arrangement which comprises providing at least three thread sections, the first thread section passing through the lining of said necktie at spaced points along the length thereof in such manner as to form free loops of said thread at such points, the second thread section passing through the lining of said necktie at spaced points along the length thereof in such manner as to form free loops of thread at such points, the said free loops of said first and second thread sections being spaced from each other across the width of said lining and the third thread section being looped around and passing freely through the said loops of said first and second thread sections to interconnect the same so as to produce a quicker acting and more positive dimple or drape.

MAX KLEINMANN.
